UNITED STATES PATENT OFFICE.

HENNING BERNHARD MATHIAS PLEIJEL AND AXEL HERMAN OLSSON, OF STOCKHOLM,
SWEDEN.

LOADING DUPLEX OR MULTIPLEX TELEPHONE-LINES.

1,215,702.

Specification of Letters Patent. Patented Feb. 13, 1917.

Application filed April 27, 1914. Serial No. 834,664.

To all whom it may concern:

Be it known that we, HENNING BERNHARD MATHIAS PLEIJEL and AXEL HERMAN OLSSON, subjects of the King of Sweden, residing at Stockholm, in the Kingdom of Sweden, have invented new and useful Improvements in Loading Duplex or Multiplex Telephone-Lines, of which the following is a specification.

- 10 By duplicatable telephone lines is meant double lines which are combined in pairs in such a manner that, in addition to the two telephonic circuits which they themselves constitute—the so-called main lines—they supply a third so-called combination or duplex line, the branches of which consist each of one of the two main lines themselves connected in parallel. With this arrangement of lines, 50% more telephonic circuits may be laid in one line than the double line actually contains. This is of great economic value, and therefore the practical "pupinization" of such lines is of great practical importance.
- 25 As is well known, ordinary double lines are most easily "pupinized" with the so-called double coils. These consist of two windings, each on one half of a ring-shaped core, and each in one branch conductor and so connected that the two currents, flowing in contrary directions in the two branches, magnetize the core polelessly. In the combination line, however, the currents in the branches of each double line flow in the same direction. They would not therefore, in the case of such coils, magnetize the cores polelessly; but at the point where the half windings touch, lines of force would respectively enter and pass out of the core. This stray field is particularly harmful; for, as a result of the necessarily close arrangement of the coils of all wires in one box, it will strike the neighboring coils and thereby give rise to cross-talk. In order to avoid this, magnetic screens might be placed around the coils. These would, however, possess the disadvantage that the eddy currents induced in them by the stray field would considerably increase the effective resistance of the compound coils. The coils have therefore been wound in such a manner that each half winding is spread over the whole of the core. Thus, even if the direction of the current be the same in both branches, there is no stray field; but the two half windings
- 30 counteract each other and the coils possess no self-induction for the combination lines.
- It has therefore been proposed, in addition to coils wound in this manner for the main lines, to connect additional similarly wound coils for the loading of the combination line; and this is done, either as described in the specification to the German Patent No. 209655, in which each main line possesses a separate set of coils for this purpose, or in 65 the manner described in "The Electrician," London, 1911, vol. 67 p. 771, in which the extra coils for the combination line are double coils, with four windings, which are connected with both main lines. There is 70 however the disadvantage common to both these proposals that, even for circuits the self-induction of which they do not increase, the coils cause an increase in resistance, and thus decrease the "pupinization." Moreover, with combination line coils wherein both main lines are conducted around a single core, it is exceedingly difficult in practice to maintain sufficient independence of the three circuits. These disadvantages had 75 however to be tolerated in order to avoid the stray field before referred to.
- With the aid of the present invention, it is possible to avoid all the disadvantages referred to by means of that very field. By a 85 suitable form of construction of the coils, the stray field is so formed that it extends within the coil arrangement which therefore remains outwardly strayless in all working connections. This stray field, which is free from the disadvantages hitherto prevailing, may then in the same coils which load the main lines, be employed for loading the combination line. In this manner, extra coils are not required. Moreover, each main 90 line is independent while its duplicatability remains unaffected.
- According to our improved method of arranging the coils, for each point of loading, two of the above described well-known 100 coils are taken; and these are connected in series or in parallel, so that they give the requisite amount of self-induction at the point of connection. These two coils are then laid symmetrically one on the other, in 105 such a manner that the divisions between the half windings which, when the stray field is produced, has dissimilar polarity, cover each other. Thus, in the case of currents flowing in opposite directions in the branches of the 110

main line, the two coils do not influence each other, as they produce in this case no external field. The arrangement acts in the same way as two ordinary compound coils 5 connected in series or in parallel. In the case of currents flowing in the same direction, however, each coil absorbs the stray field of the other. What might be called an internal stray field is however produced; and 10 the compound coils, unlike those hitherto known, remain externally strayless in all working connections. This internal stray field can now be employed for the self-induction loading of the combination line. 15 In the accompanying drawing, Figures 1 and 2 show the method of connecting a duplex line to the new coils. Fig. 3 shows a combination of the coils present in Figs. 1 and 2, but on a larger scale. Fig. 4 shows 20 a combination of coils connected in parallel. In Figs. 1 and 3, the two coils are shown in the plane of the drawing displayed side by side with the object of making the connections distinct. As a matter of fact, the two 25 coils which go together are placed, as described above and as shown in Fig. 2, one on the other, and are connected by tapes or the like so as to form what externally resembles a single coil. As may be seen in Figs. 1 and 30 3, the coils 1 and 2 of every combination are wound in the same manner as the combination coils hitherto employed for ordinary duplex lines. The half windings are respectively on the halves of a ring-shaped 35 magnetizing core and are separated by means of the disks A, B. The directions of the windings are so chosen that, in the case of a similar direction of the currents in both branches, for an instantaneous value of the 40 current in (for instance) coil 1, a north pole is produced at A, a south pole at B, and in coil 2 a north pole at B¹ and a south pole at A¹. As A falls over A¹ and B over B¹ when 45 the two coils are placed together, each coil absorbs the stray field of the other. In this manner, a magnetic flux is produced which extends over AA¹ and BB¹ and is closed through the superposed halves of the two coils and which therefore, when the direc-

tion of the current is the same in both 50 branches of the double line, is surrounded in parallel by the two branches. It thereby produces the self-induction for the "pupinization" of the combination line.

In Figs. 1 and 3, the two coils of each combination are shown in series connection. They may however be connected in parallel, as already mentioned, and as illustrated in Fig. 4, without affecting the essence of the invention, if for instance it be deemed more 60 advantageous as regards the attainment of the electrical effects desired.

The iron core may with advantage be ring-shaped. In cross section, instead of being of the usual circular or square shape, 65 it may be made rectangular and in such a manner that the long side falls in the plane perpendicular to the axis of the coil. The two coils then face each other with surfaces of greater extent; the internal stray field 70 being thereby rendered stronger and the self-induction of the combination line increased.

We claim:—

1. Duplicate double telephone lines worked 75 on the Pupin system, loaded with induction coils and wherein the coils of the main lines consist of separate windings on separate iron cores laid together and so connected electrically that the phantom line becomes 80 loaded by the stray fields created between the separate coils by the current in the phantom line.

2. Duplicate double telephone lines worked 85 on the Pupin system, and loaded with induction coils each of which consists of two double coils consisting of separate windings on separate iron cores laid together and so connected electrically that the magnetic poles created by the current on the phantom 90 line will be of opposite polarity at any one point in either pair of coils.

HENNING BERNHARD MATHIAS PLEIJEL.
AXEL HERMAN OLSSON.
